(57) **CLAIM**

The ornamental design for a short milk tube vent plug for a dairy animal milker unit, as shown and described.

DESCRIPTION

FIG. 1 is an environmental perspective view of a short milk tube vent plug for a dairy animal milker unit in accordance with the present invention, shown installed on a milk tube; FIG. 2 is an upper perspective view of the short milk tube vent plug for a dairy animal milker of FIG. 1; FIG. 3 is a lower perspective view thereof; FIG. 4 is a top view thereof; FIG. 5 is a bottom view thereof; FIG. 6 is a first side view thereof; FIG. 7 is a second side view thereof; FIG. 8 is a third side view thereof; FIG. 9 is a fourth side view thereof;

FIG. 10 is an environmental perspective view of a second embodiment of the short milk tube vent plug for a dairy animal milker unit in accordance with the present invention, shown installed on a milk tube;

FIG. 11 is an upper perspective view of the short milk tube vent plug for a dairy animal milker of FIG. 10; FIG. 12 is a lower perspective view thereof;

FIG. 13 is a top view thereof; FIG. 14 is a bottom view thereof;

FIG. 15 is a first side view thereof; FIG. 16 is a second side view thereof;

FIG. 17 is a third side view thereof; and, FIG. 18 is a fourth side view thereof.

The broken line showing of a milk tube and liner in FIGS.

1 and 10 illustratively depicts exemplary in-use components

that form no part of the design claim but are included to show the invention in context.

1 Claim, 8 Drawing Sheets
